ASH TRAY

Oscar L. Swenson, Toledo, Ohio

Application June 10, 1955, Serial No. 36,462

Term of patent 7 years

(Cl. D85—2)

Fig. 1

Fig. 2

Fig. 3

Fig. 4

Fig. 5

Fig. 1 is a side elevational view of an ash tray showing my new design;

Fig. 2 is a rear elevational view thereof;

Fig. 3 is a front elevational view thereof;

Fig. 4 is a top plan view thereof; and

Fig. 5 is a bottom plan view thereof.

I claim:

The ornamental design for an ash tray, substantially as shown.
